UNITED STATES PATENT OFFICE.

WILLIAM L. DROWN, OF WORCESTER, MASSACHUSETTS.

MACHINE FOR MAKING FLAT BANDS OR TUBE SECTIONS.

Application filed April 8, 1921. Serial No. 459,575.

To all whom it may concern:

Be it known that I, WILLIAM L. DROWN, a citizen of the United States, residing at Worcester, in the county of Worcester and 5 Commonwealth of Massachusetts, have invented a new and useful Improvement in a Machine for Making Flat Bands or Tube Sections, of which the following, together with the accompanying drawings, is a specification.

The present invention relates to the manufacture, from paper or the like, of flattened endless bands or tube sections. The invention contemplates the rapid production of 15 such articles from a travelling web of paper, or other material, which web is continuously and progressively formed into a flattened or distended tube, from the end of which the bands are successively cut off at a high 20 rate of speed.

The various novel features of the invention are set forth in detail hereinafter, reference being had to the accompanying drawings, in which—

25 Fig. 1 is a plan view showing one arrangement of mechanism in accordance with the invention.

Fig. 2 is a view in side elevation of the mechanism shown in Fig. 1.

30 Fig. 3 is an enlarged view showing a device employed for imparting flattened tubular form to the web of material.

Fig. 4 is a vertical sectional view on the line 4—4 of Fig. 3.

35 Fig. 5 is an enlarged detail view of the mechanism for gumming the web of material.

Fig. 6 is a top plan view of the gum hopper shown in Fig. 5.

40 Fig. 7 is a sectional view on the line 7—7 of Fig. 5.

Fig. 8 is an end view of the gumming mechanism.

45 Fig. 9 is an end view of the other end of the machine, showing the band cutting mechanism.

Fig. 10 is a top plan view of the cutting mechanism shown in Fig. 9.

50 Fig. 11 is a vertical sectional view of said cutting mechanism.

Like reference characters refer to like parts in the different figures.

As shown in Figs. 1, 2 and 5, the material, such as paper or the like, from which the

bands are to be made, is unwound continuously, in the form of a flat web A from a supply roll 1, the latter being mounted at any convenient point on the frame of the machine. As here shown, the supply roll 1 is disposed forwardly of a guide roll 2, 60 over which the flat web A passes on its way to the tube forming, feeding, printing and cutting instrumentalities hereinafter described.

The web A is continuously unwound from the supply roll 1 and passes forwardly of the machine in the general direction imparted thereto by the guide roll 2; the passage of the web around the guide roll 2 and its delivery, tangentially, from the top surface of said roll is availed of for the purpose of laying a line of moist adhesive along one longitudinal edge of the web in the manner now to be described.

Adjacent the guide roll 2, the machine 75 frame provides a forked bracket 3, the latter serving for the pivotal support of a bell crank lever, one arm 4 of which carries a receptacle 5 adapted to contain a heavy slow-flowing adhesive. The other arm 6 of 80 the bell crank lever extends downwardly and is attached to the frame of the machine by a yielding spring 7, tending to draw it inwardly, as shown in Fig. 5. The end of the arm 6 has a threaded enlargement 8 in 85 which works an adjusting screw 9, the end of which bears against the fixed framework. The manipulation of screw 9, which is adapted to be set in any desired position by a wing nut 10, procures a delicate adjustment, relative to the surface of the web A, of the end of an outlet tube 11, leading from the receptacle 5.

As shown in Figs. 5 to 8 inclusive, the end of the tube 11 is disposed in overlying 95 relation to one edge of the travelling web A as the latter passes over the guide roll. The axis of tube 11 is in vertical alinement, substantially, with the axis of the roll 2, and the lower or outlet end of said tube is 100 curved, as shown at 12, to conform substantially to the contour of said roll at the point where the web A is delivered tangentially therefrom. The end of tube 11 is preferably triangular in section, as shown at 13, 105 Figs. 6 and 7, whereby the adhesive which is wiped off along the edge of web A obtains its maximum width on the far side

of the opening. In this way any tendency of the adhesive to smear or spread is overcome.

The operation of the gumming devices 5 will be clear from the foregoing description; the thick slow-flowing adhesive in receptacle 5 descends by gravity through the outlet tube 11, the latter being equipped with a throttle valve 14 which is regulable to vary 10 the rate at which said adhesive is supplied, and which can be shut off entirely when the machine is stopped. The pressure of the curved end 12 of tube 11 against the web is controlled by the spring 7 and the screw 9, 15 and may be varied to suit different operating conditions and different kinds of adhesive. In this way, the mechanism can be adjusted so as to bear on the web A just sufficiently to let the proper amount of adhesive exude 20 from the end of the tube 11, said adhesive being wiped onto the edge of the travelling web in the proper amount under any condition of operation. The receptacle 5 is preferably provided with a cover 15, which is 25 adapted to be clamped down tightly to prevent access of air or any foreign matter to the adhesive.

Referring to Figs. 1 and 2, the continuous draft on the material of the web A to draw 30 it forwardly through the machine is effected by a pair of constantly rotating feed rolls 16, 16, the latter being geared together, and the lower feed roll being driven by gearing 17, 17 from a transverse shaft 18. The latter 35 carries a bevel gear 19 in mesh with a bevel pinion 20 on shaft 21, which may be rotated by worm gearing 22 from a motor or other prime mover 23. The feed rolls 16, 16 however, do not act on the flat web A, but rather 40 on the same after it has been converted into a flattened tube, by passage through suitable forming mechanism, about to be described, which forming mechanism is introduced between the gumming mechanism and the feed rolls. 45

Said forming mechanism is illustrated in Figs. 3 and 4 as carried by a suitable bracket 24 which provides support for a hollow tubular member 25. The bracket 24 also provides support for a second hollow tubular member 26 disposed inside the member 25 and projecting beyond the ends of the latter. On that portion of the member 26 inclosed 50 within the member 25 are mounted suitably formed collars 27, 27, whose maximum diameters are somewhat less than the interior diameter of member 25, to enable the web material to pass freely between said collars and said member 25. The peripheral 55 surfaces of the collars 27 are preferably curved in such a manner as to minimize the friction of the moving material, which has progressively imparted thereto a tubular form by its passage through the annular spaces 28 thus provided.

It is to be understood, of course, that the mechanism contemplates the provision of members 25 of different interior diameters, for use with various sizes of collars 27, so as to accommodate the machine to the handling 70 of webs of varying width for the production of different sized bands. As indicated diagrammatically in Fig. 2, the flat web A, after leaving the gumming mechanism, undergoes a gradual deflection to enable it to 75 enter the annular passage provided by the forming mechanism; in the latter, this deflection is augmented to the extent of causing the edges of said web to overlap, thereby passing out of the forming mechanism in 80 substantially tubular shape, and in readiness for the flattening or distending operation.

As herein illustrated, this flattening is accomplished by a pair of guide members 29, which are pivoted on the opposite sides 85 of a member 30 which is secured to the projecting end of member 26. The guide members 29 are capable of limited movement in a horizontal plane, being yieldingly drawn together by a spring 31, the force 90 of which is resisted by pins 32, 32 projecting inwardly from the guide members 29, 29 and adapted to bear on the wedge shaped adjustable member 33. The member 33 is carried by a rod 34 which extends 95 through the inner tubular member 26, said rod being adjustable by means of a nut 35, to move the member 33 in or out, relative to the end of member 26, thus either 100 distending or drawing in the guide members 29, as may be desired. It will thus be seen that said members 29 can be adjusted to suit various conditions of operation and various sizes of tubes, with the result that any given tubular section emerging 105 from the member 25, with its edges overlapped and joined by adhesive, will be flattened sufficiently by the guide members so as to pass to the feed rolls 16 in a horizontal plane; the latter therefore, as previously noted, act not upon the single thickness of flat web A but upon a double thickness of tubular section, as indicated at B, Fig. 2.

In advance of the feed rolls 16, 16 may be provided any suitable printing devices, here shown diagrammatically in the form of rolls 36, 36, the latter being driven by gearing 37, 37 from a shaft 38. Said shaft 38 carries a bevel gear 39 in mesh with a bevel pinion 40 on the opposite end of shaft 21 from the bevel gear 19. After being printed, the double thickness flattened tubular section B is in readiness to be severed transversely into bands of the desired width, this being accomplished by a reciprocating cutting mechanism at the end of the machine, designated generally by the numeral 41. The operation of this cutting mechanism involves momentary stoppages in the con- 110 115 120 125 130

tinuous travel of the tubular flattened material B, and these are compensated for without interruption of production and without decreasing the speed of the machine, in a 5 manner to be hereinafter described.

The cutting mechanism 41 provides suitable slideways 42 for a reciprocating head 43, the latter carrying a knife 44 which is adapted to cooperate with the edge of a fixed 10 support 45 to sever the end of the flat tube B projecting beyond said support. The head 43 is reciprocated by a crank connection 46 from a shaft 47, the latter being driven by gearing 48, 48 from a shaft 49 15 that has a silent chain and sprocket connection 50 with the prime mover 23.

In order to procure the projection of the flattened tube B beyond the edge of support 45, the feed rolls 51 and 52 are provided, 20 the roll 51 being fixed in the framework, while the roll 52 is carried in vertical movable standards 53, the latter being normally urged upwardly by springs 54. Said roll 52 is driven from a shaft 55 by bevel gearing 25 56, said shaft carrying on its lower end a friction wheel 57 which bears against the surface of a friction disk 58, the latter being mounted on a countershaft 59 which is connected by gearing 48 with the shaft 49.

To procure the severance of the flattened tube B by reciprocating knife 44, said tube must be clamped and held momentarily by each stroke of the knife on the support 45. This is accomplished by a clamping member 30 carried by head 43, which, in the upper position of said head, is so disposed as to leave sufficient space for the movement of flattened tube B. Adjustment of this clamping member is effected by suitable nuts 61 35 engaging the screw threaded ends of its shanks 62 which pass through the head 43. Springs 63 are provided for said shanks, to cushion the movement of the clamping member and to permit further descent of the 40 head, for the operative stroke of the knife after the tube B has been securely clamped.

The head 43 has rearwardly extending 45 projections 64, 64 carrying set screws 65, 65 which bear against the tops of the standards 53, 53 of lower feed roll 52. By this means, said feed rolls 51 and 52 are adapted 50 to be separated, and rendered inoperative, momentarily, on the descent of the head 43, which first clamps the flattened tube B in 55 stationary position between the parts 45 and 60 60 and then severs the projecting end of same by knife 44. On the upstroke of the head, the rolls 51 and 52 are quickly rendered operative to project said flattened 65 tube B a predetermined distance, as controlled by the speed adjustment of said rolls which is afforded by the friction drive of shaft 55; said speed adjustment provides the usual means, here shown as a lever 66, 70 for moving the friction wheel 57 radially

toward or from the axis of friction disk 58. As the roll 52 reaches its upper operative position, it cooperates with the roll 51 to advance the flattened tube, the latter being guided by suitable stationary members 67, 70 75 67 disposed between said rolls and the support 45.

It will thus be seen that there is an exceedingly rapid intermittent feed of the advancing end of flattened tube B by the rolls 75 51 and 52, the latter being rendered alternately operative and inoperative by the rapid reciprocations of the head 43. On the other hand, the major portion of tube B has a constant feed, by the action of feed 80 rolls 16, and hence some suitable mechanism must be provided to compensate for the two different kinds of feed and to cushion or otherwise counter-balance the effect on the tube B of the sudden and rapidly recurring 85 operations of rolls 51 and 52.

Such mechanism, as here shown, takes the form of a pair of suitably mounted yielding guide rolls 68 and 69. The roll 68, 90 around which the tube B is first led on its way from the printing mechanism, is mounted on a bell crank lever 70 pivoted at 71 to a bracket 72 of the framework. The tube B passes backwardly from the roll 68, over the top of and around roll 69, the latter being mounted on a bell crank 73 which is pivoted at 74. The other arms of the bell cranks 70 and 73 oppose each other, as shown in Fig. 2, being linked together by a 95 pivot pin 75. The latter is normally urged upwardly by an expansive spring 76, which tends to rock the rolls 68 and 69 bodily in opposite directions away from each other. On the other hand, the tension of the tube B tends to draw said rolls together against 100 the force of spring 76.

Said flattened tube B, after passing around and below the roll 69, is subject to the action of a suitable friction device, here shown as a spring pressed roller 77 which 105 pinches the tube against a stationary member 78. The friction device imparts a slight drag on the flattened tube B so as to act as a brake thereon against undue movement of same either by the rolls 51, 52 or by the 110 rolls 68 and 69.

The operation of the mechanism will be clear from the foregoing description. The constant feed of the flattened tube section B by the rolls 16, 16 is taken care of, during the momentary stoppages of rolls 51 and 52, by the vibrating rolls 68 and 69. When the rolls 51 and 52 are separated, for the instant that the end of the tube B is clamped 120 on the support 45, said tube B is maintained taut by the ensuing slight separation of rolls 68 and 69, under the influence of spring 76. On the other hand, when the rolls 51 and 52 are brought together, and thereby 125 cause forward movement of the tube at a 130

slightly faster rate than that imparted by the rolls 16, 16, the rolls 68 and 69 yield toward each other, thereby preventing any undue strain of tension on the tube.

5. I claim,

1. In apparatus of the class described, the combination with feeding means, of a forming device operable in advance of said feeding means, to impart a substantially cylindrical tubular section to a continuous single sheet of material, and a device interposed between said forming device and said feeding means for distending said tubular section, whereby to present it in substantially flattened form to said feeding means.
2. In apparatus of the class described, the combination with feeding means, of means disposed in advance thereof for progressively imparting tubular form to a travelling single sheet of material, said forming means being replaceable by similar means of different size for sheets of different width, and means associated with said forming means and interposed between said forming means and said feeding means for distending said tubular section, whereby to present it to said feeding means in substantially flattened form, said distending means being adjustable for tubes of different size.
3. In apparatus of the class described, means for applying a line of adhesive to a travelling web of material, said means comprising a roll around which said web passes, and a superposed adhesive supply device presenting a definite area for the gravity

movement of adhesive onto said web at the point of its tangential passage off of said roll in a horizontal plane.

4. In apparatus of the class described, means for applying a line of adhesive to a travelling web of material, said means comprising a roll around which said web passes, a superposed adhesive supply device presenting a definite area for the gravity movement of adhesive onto said web at the point where said web passes tangentially off of said roll, in a horizontal plane and means for adjusting the pressure of said adhesive supply device on said web and roll.

5. In apparatus of the class described, the combination with a roll around which passes a travelling web, of a confining means for the gravity flow of adhesive material onto said web, the outlet of said confining means conforming substantially to the curvature of said roll at the point where said web passes tangentially off of said roll in a horizontal plane.

6. In apparatus of the class described, the combination with a roll around which passes a travelling web, of a confining means for the gravity flow of adhesive material onto said web, the outlet of said confining means conforming substantially to the curvature of said roll at the point where said web passes off of said roll, and said outlet increasing in width toward the direction of travel of said web.

WILLIAM L. DROWN.
